UNITED STATES PATENT OFFICE.

RICHARD BOSELLEMMANN, OF BERLIN, GERMANY.

PRESSURE-REGULATING DEVICE FOR INTERMEDIATE STEAM-WITHDRAWAL INSTALLATIONS.

Application filed June 17, 1921. Serial No. 478,421.

(GRANTED UNDER THE PROVISIONS OF THE ACT OF MARCH 3, 1921, 41 STAT. L., 1313.)

To all whom it may concern:

Be it known that I, RICHARD BOSELLEMMANN, a resident of Berlin, Germany, of German nationality, have invented certain new and useful Improvements in Pressure-Regulating Devices for Intermediate Steam-Withdrawal Installations (for which I have filed application in Germany Dec. 27, 1918, Patent No. 333,296), of which the following is a specification.

In order to maintain constant the receiver pressure which fluctuates with the load on the steam engine and thereby to permit use of the quantity of steam drawn off with uniform pressure, in most cases the regulation of the cut-off of the low pressure cylinder was automatically made dependent on the draw-off pressure.

In steam engines which previously were not fitted with this regulating device the subsequent fitting of the controlling means presents difficulties and for this reason the simpler though less economical method of fitting stop valves in the draw-off pipe and in the pipe leading to the low pressure cylinder has been employed. These two valves are positively connected with one another and in their movement are dependent on the draw-off pressure to be maintained constant in such manner that according to the load on the engine or the quantity of steam to be drawn off the one valve is closed by the same amount as the other is simultaneously opened and vice versa. The total cross sectional passage area of both valves is thus at all times and in any position equal to the total cross section only of one valve so that these valves must be of excessively large cross section if throttling is to be avoided.

Hereinafter is described a new arrangement in which objectionable throttling is avoided, both valves opening to the full extent on normal load on the engine and with the most favourable steam draw-off quantities.

The improved regulating device is illustrated in the accompanying drawing in which Fig. 1 is a view of the whole arrangement while Fig. 2 shows to enlarged scale the auxiliary controlling piston, the return sleeve and the pressure fluid path.

As shown, the steam flowing from the high-pressure cylinder passes first into a T-shaped piece t , and from there one part

flows through the throttle valve d^2 to the low-pressure cylinder, the other part flowing through the throttle valve d' to the place where it is to be used. Both throttle valves are moved by a common regulating device (shown in the drawing) the central position of which corresponds exactly to the normal engine load, one part of the quantity of steam coming from the high pressure cylinder flowing to the low pressure cylinder, the other part to the place of use.

Both throttle valves are in this central position fully open. The pressures in the receiver and behind the two throttle valves are thus equal at the two measuring points s' and s^2 of the duplex manometer.

The auxiliary piston k moved by the pressure fluid, the small auxiliary controlling piston i and the diaphragm m under the influence of the draw-off pressure are also in middle position. The auxiliary controlling piston i is connected directly with the diaphragm m and is moved in a sleeve h provided with passages, the movement of which sleeve positively by a lever transmission is dependent on the movement of the auxiliary motor piston k . This intermediate piston fulfils the same requirements as the return in the direct regulators (servo motors) but has the advantage that its sensitiveness can be varied within wide limits since the joint g is adjustable with respect to the fixed pivot p so that the movement of the sleeve can be regulated to zero and highly sensitive regulation obtained. In most cases, however, less sensitiveness for example of 5% will be sufficient.

If now a greater load is put on the engine or a reduction in the consumption of steam at the place of use takes place, an increase in the pressure at t occurs. By the increase of pressure the diaphragm m is pressed downwards out of its position of equilibrium and the flow of oil under pressure to the space above the auxiliary piston k is permitted by the auxiliary piston i . The servo-motor piston k is in consequence moved downwards until by the adjustment of the throttle valve d' the pressure has decreased again at the point s' and the sleeve h has correspondingly stopped the movement of the piston k by covering the oil pressure passages. If steam is cut off from

the point at which it is consumed the throttle valve d' is closed and the lever n assumes its lowest position indicated by the lower dotted line.

5. The throttle valve d' will again open as soon as steam is taken at the point of consumption; the weight o prevents the throttle valve d^2 from being closed before d' is fully open.

10. If an increased amount of steam is drawn off or the load on the engine falls the pressure in t is reduced. The servo motor piston is thereby moved upwards in the reverse direction until the throttle valve d^2 by 15 throttling the steam flowing to the low-pressure cylinder has restored the normal pressure in t or through the open throttle valve d' the pressure at the point s' . When the throttle valve d^2 is fully closed the lever n 20 is in its highest position shown in the drawing by the upper dotted line. Thus it will be seen that either both valves d' and d^2 may be moved alternately or either one of them, the other remaining stationary, depending upon the draw-off pressure.

25. The relative dependence of the two throttle valve positions can also be effected positively or by interlocking in lieu of by the weight. The movements of the two 30 throttle valves in consequence of this dependence do not coincide in point of time.

35. In order to prevent too great a quantity of steam being drawn off or too great throttling of the steam flowing to the low pressure cylinder there is arranged a double manometer connected beyond the two throttle valves by means of which the control can be conveniently effected.

I claim—

40. 1. In an apparatus for regulating the drawing off pressure in the intermediate steam withdrawal in steam engines a stop-valve arranged in the draw-off pipe and another stop-valve in the pipe leading to 45 the low-pressure cylinder these valves being separately and automatically controlled under the influence of the draw-off pressure.

50. 2. In an apparatus for regulating the drawing off pressure in the intermediate steam withdrawal in steam engines a stop-valve arranged in the draw-off pipe and another stop-valve in the pipe leading to the low pressure cylinder, these valves being 55 separately controlled by a servomotor under the influence of the draw-off pressure.

3. In an apparatus for regulating the

drawing off pressure in the intermediate steam withdrawal in steam engines a stop-valve arranged in the draw-off pipe and another stop-valve in the pipe leading to the 60 low-pressure cylinder, these valves being alternately controlled by a servomotor under the influence of the draw-off pressure, and a double armed lever loaded by a weight and journalled on the rod of the servomotor 65 piston, two rods connecting the ends of said lever to the throttle valves in the steam pipes.

4. In an apparatus for regulating the drawing off pressure in the intermediate 70 steam withdrawal in steam engines a stop-valve arranged in the draw-off pipe and another stop-valve in the pipe leading to the low-pressure cylinder, these valves being alternately controlled by the servomotor under the influence of the draw-off pressure 75 actuating a piston valve gear in a movable sleeve with inlet and outlet ports, said sleeve forming a stop valve and being connected by an adjustable lever transmission 80 to the servomotor piston.

5. In an apparatus for regulating the drawing off pressure in the intermediate steam withdrawal in steam engines a stop-valve arranged in the draw-off pipe and another stop-valve in the pipe leading to the low pressure cylinder, these valves being alternately controlled by a servomotor under the influence of the draw-off pressure, and a double armed lever loaded by a weight and 90 journalled on the rod of the servomotor piston, two rods connecting the ends of said lever to the throttle valves in the steam pipes, and a piston valve gear working under the influence of the draw off pressure 95 in a movable sleeve with inlet and outlet ports, said sleeve forming a stop valve and being connected by an adjustable lever transmission to the servomotor piston.

6. In an apparatus for regulating the 100 drawing off pressure in the intermediate steam withdrawal in steam engines, a stop valve arranged in the draw-off pipe, and another stop valve arranged in the pipe leading to the low pressure cylinder, said 105 valves being separately and automatically controlled under the influence of the draw-off pressure and capable of fully opening their respective pipes without throttling.

In testimony whereof I affix my signature.

RICHARD BOSSELMANN.
